UNITED STATES PATENT OFFICE.

ORRIN JOSEPH BUJOL, OF ESTHERWOOD, LOUISIANA.

GAUGE PLATE FOR RAILS.

Application filed July 30, 1925. Serial No. 47,096.

To all whom it may concern:

Be it known that I, ORRIN JOSEPH BUJOL, a citizen of the United States, residing at Estherwood, in the parish of Acadia and 5 State of Louisiana, have invented certain new and useful Improvements in Gauge Plates for Rails, of which the following is a specification, reference being had to the accompanying drawings.

10 This invention relates to gauge plates for rails and more particularly to a rail seat so constructed that it provides means for holding a gauge rod, preventing spreading of the rails, and against movement longitudinally 15 of the rail sections.

A further object of the invention is to provide a device of this character which may be applied to the tie and the tie slid into place to replace an old tie which is being 20 removed.

A still further object of the invention is to provide a device of this character which may be cheaply and readily produced, which will be durable and efficient in service and 25 a general improvement in the art.

These and other objects I attain by the construction shown in the accompanying drawings, wherein for the purpose of illustration is shown a preferred embodiment of 30 my invention and wherein:—

Figure 1 is a plan view of a section of track having gauge plates constructed in accordance with my invention;

Figure 2 is an enlarged sectional view 35 through the track as shown in Figure 1;

Figure 3 is an enlarged transverse sectional view through a pair of chairs and rails supported thereby showing the mounting of the gauge rod;

40 Figure 4 is a perspective of a single gauge plate;

Figure 5 is a perspective of one end of the gauge rod.

Referring now more particularly to the 45 drawings, the seat comprises a rectangular plate 10 which is preferably approximately two inches in thickness and which has the end portions of its upper face, indicated at 11, beveled from the ends of the plate so that the thickness of the plate at its ends is approximately one-half the normal thickness of the plate or, in the present instance, one inch. At the outer edge of the beveled portion 11 at one end of the plate a transversely extending upstanding rib 12 is

formed, the purpose of which will presently appear.

The upper surface of the plate is subdivided longitudinally of the two sections by a longitudinally extending channel 13 subdividing the upper surface into two sections 14 and 15 upon which the flange F of the rail R seats. Each beveled portion 11 associated with the sections 14 and 15 has formed therein a spike receiving opening 16. The 60 sections 14 and 15 are the same length as the width of the rail and the spike openings 16 are formed so that the heads of the spikes will properly overlie the rails. At its outer end, this channel is enlarged, as at 17, this 65 end being that end adjacent the rib 12. At this enlarged end, the plate has a vertically extending opening 18 formed therethrough.

In applying the plates, the plates are set 70 in position with their ribs 12 outermost and 75 may be applied to the tie before the same is shifted into position on the right of way. After the tie has been placed, the rails are settled into position and the spikes driven home, thus firmly holding both the plates 80

and the rails. At intervals, the anti-spreading gauge 19 is applied, this gauge comprising a flat bar 20 adapted to engage the tie between the plates 10 and having its ends 85 vertically offset, as at 21 and 22. These ends 21 and 22 extend through the channels of the plates and are concealed therein and the end 21 has formed thereon a hook 23 adapted to receive the outer edge of the flange of the corresponding rail. The end 22 has its extremity rounded and screw-threaded, as indicated at 24, and has slidably mounted thereon an element 25 having a shank portion 26 adapted to enter the opening 18 of the plate and which shank portion is provided with an opening 27 for the passage of 90 the threaded portion 24 of the end 22 of the bar. The shank has an angular extension 28 adapted to overlie and engage against the face of the outer portion of the flange of 95 the second rail. The element 25 may be adjusted longitudinally by means of nuts 29 to draw the rails toward one another and maintain the same in their proper positions.

It will be obvious that in spreading, the 100 flanges of the rails will engage against the ribs 12 and that these flanges will tend to prevent this spreading. This tendency to separate or spread, when noted, may be readily cured by tightening up upon the 110

gauge rod 19 in the usual manner. It will also be obvious that the construction hereinbefore set forth is capable of a certain range of change and modification without materially departing from the spirit of my invention and I accordingly do not limit myself to such specific structure except as herein-after claimed.

I claim:—

- 10 1. A gauge plate for rails having a seat for the flange of the rail, said plate having openings formed therethrough for the passage of spikes at opposite sides of the rail, said plate having in its upper surface a longitudinally extending channel transversely dividing the rail seat.
- 15 2. In combination with a tie, a pair of plates mounted upon opposite ends thereof and each providing a seat for the flange of a rail, said plate having at the outer edge of the flange seat thereof an upstanding ridge, the plates being formed with aligned channels subdividing the rail seats thereof and a gauge rod having its ends directed 25 through said slots and provided with hooks for engagement with the outer edges of the flanges of rails applied to the seat.
- 20 3. In combination with a tie, a pair of

plates mounted upon opposite ends thereof and each providing a seat for the flange of a rail, said plate having at the outer edge of the flange seat thereof an upstanding ridge, the plates being formed with aligned channels subdividing the rail seats thereof and a gauge rod having its ends directed 30 through said slot and provided with hooks for engagement with the outer edges of the flanges of rails applied to the seat, said gauge rod being adjustable as to effective length.

4. In combination with a tie, a pair of gauge plates secured thereto and adapted for the reception of rails, each of said plates having a portion adapted for engagement by the flange of the rail when the rails are 40 properly spaced and with which the rails engage upon spreading thereof whereby they resist said spreading, said plates being each provided with a channel directed longitudinally of the tie and permitting passage of 45 a gauge clamp having means to engage the outer side edges of the flange of the rail applied to the plates.

In testimony whereof I hereunto affix my signature.

ORRIN JOSEPH BUJOL.
